UNITED STATES PATENT OFFICE.

JOHN R. REYNOLDS, OF HARTFORD, CONNECTICUT.

GOVERNING MECHANISM FOR THROTTLE-VALVE CLOSERS.

SPECIFICATION forming part of Letters Patent No. 604,840, dated May 31, 1898.

Application filed February 28, 1898. Serial No. 671,889. (No model.)

To all whom it may concern:

Be it known that I, JOHN R. REYNOLDS, a citizen of the United States, residing at Hartford, in the county of Hartford and State of Connecticut, have invented certain new and useful Improvements in Governing Mechanisms for Throttle-Valve Closers, of which the following is a specification.

This invention relates to the mechanisms which are employed for controlling the movements of throttle-valve closers of the class set forth in United States Letters Patent Nos. 599,013 and 599,014, granted February 15, 1898.

15 The object of the present invention is to provide a simple and durable mechanism which will easily and quickly, but with little motion, exercise sure and perfect control over the movements of such a closer when set in 20 operation by a powerful spring or weight for closing a large or small throttle-valve.

The embodiment of the invention illustrated by the accompanying drawings has a spring or weight actuated spindle with a wheel 25 adapted to be connected with a wheel on the spindle of the throttle-valve to be closed, a train of differential gears connected so as to be brought into operation by the rotation of the spindle, and a plural number of pistons 30 located in oppositely-facing cylinders and provided with means whereby they simultaneously receive very slow motion in opposite directions from the rapid rotation of the spindle through the action of the speed-reducing 35 gears, as more particularly hereinafter described, and pointed out in the claims.

Figure 1 of the drawings illustrates a plan of a throttle-valve closer embodying the invention with the cover removed and the electric tripping means omitted. Fig. 2 illustrates a vertical section of the same closer, taken longitudinally of the spindle. Fig. 3 illustrates a vertical section taken transversely of the spindle through the oppositely-facing controlling-cylinders; and Fig. 4 illustrates a vertical section taken transversely of the spindle through the oppositely-facing controlling-cylinders, showing a modified arrangement of connecting the pistons.

50 The case 1 may be built of any suitable material to any approved shape for inclosing the

mechanisms. The spindle 2 is supported by standards 3 and 4. Outside of the case the spindle bears a pulley 5, upon the periphery of which a weight cord or band may be wound 55 to rotate or aid in the rotation of the spindle, if necessary. Adjustably attached to the pulley is a sprocket-wheel 6, that is adapted to be connected by a common sprocket-chain with a corresponding sprocket-wheel on the spindle of any throttle-valve which it is desired to be closed by the operation of the closer. Inside of the case the spindle bears a barrel 7, that is adapted to receive any common form of driving-spring. One end of the driving-spring may be attached to the walls of the barrel, while the other end may be attached to the stud 8, that is held by the standard 9 and is used to assist in supporting the barrel. Either a spring or a weight, or both, 60 may be utilized as a source of motive power. When the throttle-valve is opened through the sprocket wheel and chain, the spindle is rotated and the power of the spring or weight, or both, as the case may be, is stored for rotating the spindle in the reverse direction and closing the valve when an emergency arises and instant stopping of the engine is necessary. Any common form of catch and 65 trip mechanisms, such as set forth in the above-mentioned patents, may be used for retaining the parts set and for tripping the catch when instantaneous action is required.

Mounted upon a stud projecting from the spring-barrel is a gear 10. This gear meshes 75 with a pair of differential gears 11 and 12, one of which is fast to the standard 3 and the other attached to a sleeve 13, that is loosely supported by the standard. One of the gears has more teeth than the other, and as the 80 barrel-gear revolves the gear attached to the sleeve is rotated very slowly. This greatly increases the relative rate of rotation between the spindle and sleeve.

On the end of the sleeve opposite the differential gears is a gear 14. In the arrangement shown in Figs. 1, 2, and 3 this is a spur-gear, and meshing with the upper and lower teeth are the teeth of racks 15. These racks are formed on rods that extend in opposite 90 directions and are connected with oppositely-facing pistons 16, that are free to reciprocate 100

in short cylinders 17, supported by the bottom of the case on opposite sides of the spindle.

The pistons are cylindrical in form and are provided with oppositely-facing cup-packings 18 and packing-retaining rings 19. Extending from each of the pistons is a semicircular hub 20. Each of these hubs fits the back of and aids to retain in position the piston-rod 10 that is connected with the opposite piston, so that the rack-teeth will properly mesh with the gear-teeth. These hubs also assist in guiding the pistons in their movements into and out of the cylinders. The piston-rods loosely 15 fit into openings through the pistons, and they push the pistons in by means of shoulders 21 and pull the pistons out by means of pins 22 or equivalent means. The hubs 23 on the pistons are provided with packings 24, and the 20 piston-rods are allowed some movement, so that when forcing the pistons into the cylinders the shoulders 21 will press against the packings 24 and prevent the outflow of air; but when drawing out the pistons the shoulders 25 will move away from the packings and permit the entrance of air into the cylinders through the pistons and thus facilitate the movements of the mechanisms when the throttle-valve is being opened. This manner 30 of connecting the pistons relieves the spindle and bearings from one-sided strain, for the pistons work in opposite directions, and the rack-teeth of one engage the top and the rack-teeth of the other engage the bottom teeth of 35 the gear on the sleeve that is rotated by the motion of the differential gears. In this form the pistons aid in retaining the racks in position and the piston-rods with the racks assist in guiding the pistons in their movements, so there will be no jamming or binding. 40

In the form of connection illustrated by Fig. 4 of the drawings the driving-spindle is provided with a spiral gear 26—that is, a gear with teeth arranged as short portions of spirals 45 or screw-threads of quick pitch. Meshing with this spiral gear is a spiral gear 27, having teeth arranged in the same manner and on the same angle. The gear 27 is mounted on a shaft 28, that is supported by a forked stand- 50 ard 29. The shaft 28 is provided on one end with a right and on the other end with a left hand screw-thread, and these screw-threads engage similarly-threaded hubs 30, projecting from the piston-heads. The rotation of the 55 intermeshing spiral gears rotates the shaft, which through engaging screw-threads causes the pistons to travel back and forth simultaneously in opposite directions in the oppositely-arranged cylinders.

60 The differential gears permit a rapid and

continued rotation of the spindle, which gives a quick and extended movement to the operating parts and so greatly reduces the speed that the pistons are obliged to move but a very short distance and to travel but slowly. The 65 arrangement of oppositely-working pistons in oppositely-facing cylinders permits this great reduction of speed and movement and still provides a powerful controlling means, for the combined areas of the pistons working oppositely is large, and although moving but short distances the resulting action of both is such that perfect and sure control can be, with a short movement, exercised over a powerful and rapid-running driving means. 70

The arrangements shown permit the use of powerful actuating means, and this enables the closer to be used successfully with large throttle-valves as well as small. The relations of the controlling mechanisms are such that 80 the rotating parts are relieved of undue strains. The controlling mechanisms placed in the manner described can be made very compact, for powerful control is exercised with a very short movement of the pistons. This 85 also permits a perfect working device to be built by ordinary labor in an inexpensive manner.

I claim as my invention—

1. In combination with the motive mechanisms of a throttle-valve closer, cylinders located on opposite sides of the driving-spindle, a speed-reducing mechanism connected with the driving-spindle, and oppositely-facing pistons movable within the cylinders and provided with parts connected by intermeshing teeth with the speed-reducing mechanism and adapted to be given very slow short rectilinear movements in opposite directions in the cylinders by the rotation of the speed-reducing mechanism and connected parts, substantially as specified. 90

2. In combination with the motive mechanisms of a throttle-valve closer, a plural number of cylinders located on different sides of the driving-spindle, a speed-reducing mechanism connected with the driving-spindle, and a plural number of pistons movable within the cylinders and provided with parts connected by intermeshing teeth with the speed-reducing mechanism, which parts are so arranged that the pistons move simultaneously oppositely and each of the parts assists in guiding the opposite piston from that to which it is connected, substantially as specified. 100
